DISCONNECTION SWITCH FOR HIGH TENSION ELECTRIC LINES

Application filed March 27, 1930. Serial No. 439,421.

This invention relates to switches, and means for operating the same. More particularly, it relates to the disconnecting switches commonly employed in high tension outdoor installations. Modern electrical practice involves the use of very large and heavy insulating structures, and connecting and disconnecting switches between the same in outdoor installations of various kinds, such, for example, as those employed in sub-station work. Since these switches are rather infrequently operated, and sometimes are not operated at all, over long periods of time, it is sometimes quite difficult to operate them by lever mechanism, or the like, from such a distance as to insure the safety of the operator. Further, the switches are sometimes encrusted with sleet or ice, which interferes with their easy operation.

It is the primary purpose of the present invention to provide a switch structure to which a series of impacts or blows may be imparted when it is desired to open the same, for the purpose of loosening the engagement between the blade of the switch and the contact plates with which it engages. The means by which this is accomplished will be more fully pointed out in conjunction with the accompanying drawings, wherein

Fig. 1 is a side elevation showing a plurality of insulating structures, and the disconnecting switch therebetween,

Fig. 2 is a partial plan view of the structure of Fig. 1,

Fig. 3 is an enlarged side view of one of the insulators, illustrating the contact tongues carried thereby, and between which an end of the switch blade is received,

Fig. 4 is a horizontal sectional view upon line 4—4, of Fig. 1,

Fig. 5 is a vertical sectional view upon line 5—5 of Fig. 2, and

Fig. 6 is a fragmentary sectional view of the central or switch actuating insulator, and associated parts.

Like numerals designate corresponding parts in all of the figures of the drawings.

Referring to the drawings, the numeral 5 designates a centrally arranged insulating structure which is adapted to be oscillated

about its axis by a shaft 6. The insulator 5 is provided with a cap 7, and this cap has a base plate 8 secured thereto by the screws 9. The switch blade consists of a pair of plates 10—11, which are brought together to form 55 the knife-like ends 12. At their intermediate portions, these plates lie in spaced relation to each other, and the necessary rigidity is imparted to the switch blade structure by the channel braces 13, bridges 14 and the tie-bolts 15, which traverse the plates and spacing sleeves 16, and serve to secure the bearing block 17 to the underside of the switch blade. This bearing block is traversed by a pivot stud 18, which is carried by the insulator cap 7. Thus, the block 17 and the switch blade are pivoted for limited movement with respect to the insulator cap. The base plate 8 carries a pair of U-shaped impact members at its opposite ends, the intermediate portion of said members being traversed by bolts 20, which pass through the outer ends of the base plate. The switch blade lies between the upstanding end members 21, of these U-shaped brackets. A 70 spring 22 is connected to one of the arms of each of the said U-shaped brackets, the other ends of said springs being secured to the angle braces 13. These springs are of such weight as to merely draw the switch blade 75 into alignment with the base plate, at which time one of the upstanding arms 21 of each of the impact members or brackets lies in engagement with an edge of the switch blade, but by referring to Fig. 2, it will be seen that one of these arms lies upon one side of the switch blade, while the other of said arms lies upon the other side of the switch blade.

The knife ends 12, of the switch blade, are adapted to enter between and make electrical contact with spring tongues 23, of the electrical conductors, that are to be brought into electrical connection with each other by the switch, these spring tongues projecting, as shown, from the companion insulator structures 24 and 25 disposed upon opposite sides of the central insulator 5.

From the foregoing description, it will be apparent that if the switch blade is held 100 against easy movement by its engagement

with the spring tongues 23, a quick turning movement of the insulator 5, and its cap 7, in the proper direction, will impart such movement to the base plate 8 as to strike the 5 upstanding end members 21 against the edges of the blade, the thrust being in opposite directions upon opposite sides of the center, constituted by the pivot 18. Thus, nicely balanced but forcible blows are imparted to 10 the blade upon opposite sides of the same to simultaneously jar the knife ends 12 loose from their engagement between the tongues 23. As soon as the knife ends are loose from their engagements between tongues 23, the 15 springs act to restore the blade to the position against the closing and locking in arms 21 of the U-shaped brackets, thereby preventing lost motion on the closing swing of the blade.

20 Any suitable means may be employed for oscillating the shaft 6, about its axis. For this purpose, I have indicated a cross arm 6^a, upon the lower end of the shaft, it being common practice to actuate arms of this character by any suitable form of link connections from other points. Any of the commonly employed ways of securing the several sections of the insulator structure together may be employed, these constituting no part of 25 the present invention, which resides in the means for imparting a blow to the switch blade, irrespective of the particular means for mounting the same.

30 Having described my invention, what I 35 claim is:

1. In a heavy duty switch, comprising a switch blade pivoted between its ends and having contact elements with which the opposite ends of the switch blade engages, of 40 a base mounted for free swinging movement with respect to the blade of such weight as to impart hammer-like blows to the opposite sides of the switch blade upon the opposite sides of its pivot point for the purpose of 45 loosening the switch blade from its engagement with the contact elements.

2. The combination with a heavy duty switch, comprising a switch blade pivoted intermediate its ends for oscillatory movement, of an oscillating base having lost motion engagement with the switch blade upon opposite sides of its pivot point, and contact members with which the free ends of the switch blade engage said base being capable 55 of such free movement and being of such size and weight as to impart hammer-like blows to said switch blade.

3. The combination with a heavy duty dis- 60 connector switch, comprising a switch blade pivoted intermediate its ends for oscillatory movement, of an oscillating base having lost motion engagement with the switch blade upon opposite sides of its pivot point, contact members with which the free ends of the 65 switch blade engage, said base being capable

of such free movement and being of such size and weight as to impart hammer-like blows to said switch blade, and spring means tending to move the base to one of its limits of movement with respect to said switch blade. 70

4. The combination with a switch blade pivoted for oscillatory movement, of an oscillating base carrying at its outer portion a pair of upstanding arms between which the switch blade moves, and means for drawing the switch blade into engagement with one of said arms. 75

5. In a heavy duty structure of the character described, the combination with an oscillatory base plate pivoted intermediate its 80 ends and carrying a pair of outstanding arms at its opposite ends, of a switch blade pivoted with respect to the base plate and movable between the arms of said base plate, as and for the purposes set forth, said base 85 being capable of such free movement and being of such size and weight as to impart hammer-like blows to said switch blade.

6. A structure as recited in claim 5, in combination with spring means tending to move the switch blade into engagement with one of the arms of each pair of upstanding arms. 90

7. In a switch structure, the combination with an oscillatory base plate, and means 95 for imparting oscillation to the same, of a switch blade pivotally mounted with respect to the base plate, a pair of upstanding arms at each end of the base plate between which the switch blade moves, said arms being so 100 positioned that one arm of each pair engages the switch blade upon one edge of the same, and an arm of the other pair of upstanding arms normally engages the switch blade upon its opposite edge, the distance between said 105 arms being materially greater than the width of the switch blade so that a lost motion engagement exists between these parts, and so that the arms of the pairs which normally lie out of contact with the switch blade, may be 110 forcibly impacted against said switch blade and upon opposite sides thereof, by a turning movement of the base plate with respect to the switch blade.

8. A structure as recited in claim 7 in combination with spring means normally tending to draw the switch blade into engagement with one of the arms of each pair of arms. 115

9. A structure of the character described, comprising a heavy insulator, means for imparting turning movement thereto, said insulator comprising a cap member, a base plate secured to said cap member, a switch blade pivoted for horizontal oscillation with respect to the cap and base plate, a U-shaped bracket secured to each extremity of the base plate, between the upturned portions of which the said switch blade lies and moves, the distance between the arms of the U-shaped 120 125 130

brackets being materially greater than the width of the switch blade to provide a lost motion engagement between these parts, and springs connecting one of the arms of each ⁵ U-shaped bracket with an adjacent portion of the switch blade, as and for the purposes set forth.

10. A structure as recited in claim 11, in combination with a separate insulating structure upon each side of the first named insulating structure, and contact fingers carried by the last named insulating structure, and lying in the path of movement of the free ends of the switch blade.

15 In testimony whereof I affix my signature.
FRANCIS H. UPTON.
